Primary Examiner — Eliza Z Harvey*Assistant Examiner* — Kayla Marie Bennett(74) *Attorney, Agent, or Firm* — Tristan A. Fuierer; Casimir Jones, SC(57) **CLAIM**

The ornamental design for a locking device, as shown and described.

DESCRIPTION

FIG. 1 is a perspective view;

FIG. 2 is a front view;

FIG. 3 is a top view;

FIG. 4 is a left side view;

FIG. 5 is a rear view;

FIG. 6 is a bottom view; and,

FIG. 7 is a right side view.

The device is a locking device. The broken lines in the drawings depict portions of the locking device that form no part of the claimed design.

1 Claim, 7 Drawing Sheets(56)
